(57) **CLAIM**

The ornamental design for a golf ball container, as shown and described.

DESCRIPTION

FIG. 1 is a top plan view of the golf ball container showing my new design;

FIG. 2 is a bottom plan view thereof;

FIG. 3 is a front elevation view thereof;

FIG. 4 is a right side elevation view thereof; and,

FIG. 5 is a rear elevation view thereof.

The broken line showing of golf balls is for illustrative purposes only and forms no part of the claimed design.
